UNITED STATES PATENT OFFICE

FREDERIC J. FLACH, OF CINCINNATI, OHIO, ASSIGNOR TO THE METAL SPECIALTY COMPANY, OF CINCINNATI, OHIO, A CORPORATION OF OHIO

CIGARETTE DISPENSER

Application filed July 27, 1932. Serial No. 624,954.

My invention relates to cigarette dispensers, and particularly to a cigarette dispenser for attachment within a motor vehicle.

It is the object of my invention to provide a cigarette dispenser which may be secured to the dashboard of a motor vehicle, and which will dispense cigarettes one at a time, depositing them directly in the hand of the person operating the dispenser.

Another object of my invention is the provision of a cigarette dispenser which will be simple to operate, and which can be constructed inexpensively from pressed metal.

Specifically it is an object of my invention to provide a compartment having a spring-actuated dispensing guide which, when the guide is actuated by the fingers, will project a cigarette directly into a person's hand.

Most dispensers of the type to which this invention relates have shelf portions into which the article dispensed is projected, the user then removing the article from the shelf portion. Another object of my invention is the provision of a dispenser which may be readily removed from a supporting bracket, and in which the bracket is provided with means for attachment in some position of convenient access to the driver or occupant of a motor vehicle.

The above objects and other objects to which reference will be made in the ensuing disclosure I accomplish by that certain combination and arrangement of parts of which I have shown a preferred modification.

In the drawing:—

Figure 1 is a front elevation of the dispenser.

Figure 2 is a sectional view of Figure 1, taken along the lines 2—2 of Figure 1.

Figure 3 is a sectional view showing the dispenser in the position in which a cigarette is about to be dispensed into a person's hand, the position of the fingers in operating the device being illustrated in dotted lines.

The cabinet is preferably formed from a blank pressed into rectangular shape and forming a front wall 1, side walls 2, and a rear wall 3. The metal may be suitably embossed or decorated to give the appearance of wood. The top 4 is hinged in position by

means of hinge pins 5. The top may be moved up to a position parallel with the rear wall, and cigarettes may be filled into the compartment in the obvious manner.

The box or compartment has a dispensing opening 6 with an abruptly terminated lower edge, and a bottom clearance slot 7 which permits the protruding lower end 8 of an inclined guide member 9 to be actuated leaving a stop between the opening 6 and slot 7. The guide member 9 curves downwardly and has an abutment 10 between which and the opening 6 a cigarette drops when the guide is actuated. The upper end of the guide has down-turned ears 11 which may be suitably mounted in openings 12 in the rear wall.

The back wall is slotted and pressed outwardly to form spaced loops 13, 13a, which receive the spaced tongues 14, 14a, of a bracket 15 which may be provided with a thumb nut 16 which will permit the bracket to be conveniently mounted within the motor vehicle, for example, on the dashboard.

A spring 17 within the compartment tends to urge the guide 9 to the position shown in Figure 2.

A supply of cigarettes is placed within the compartment, and when it is desired to remove a cigarette the fingers are pressed against the lower end 8 of the guide, and the guide is pushed to the position shown in Figure 3, upon which a cigarette rolls in front of abutment 10 onto the stop. As soon as the pressure of the fingers is released, the guide 9 is pushed forward by spring 17, and the cigarette will be automatically ejected by abutment 10 through the slot 6 into the fingers so that it may be readily grasped.

As far as I am advised, the dispenser forming the subject matter of this application is the only one in which the cigarette is automatically ejected into the fingers at the time that the fingers are normally in the position necessary to actuate the dispensing mechanism.

Having thus described my invention, what I claim as new and desire to secure by Letters Patent, is:—

1. A cigarette dispenser comprising a receptacle with upstanding front, back and

side walls and a bottom, having a dispensing opening in the lower part of its front wall and having a clearance slot in its bottom, spaced back from said dispensing opening, 5 leaving a stop portion at the rear of the dispensing opening, a guide comprising a curved plate with its upper end hinged to the upper portion of the receptacle adjacent the back thereof, said plate curving down and forward and then abruptly downward, then abruptly backward, and finally abruptly downward, forming an ejecting abutment at the rear of said dispensing opening by its forward, downward and backward curvature, 10 and forming a manipulating extension by its final downward curvature, said extension projecting down through said clearance slot, the downward and forward curvature of said plate forming a support and guide for the cigarettes to pass singly down between the abutment and the dispensing opening as the plate is swung backward, the cigarette resting on the stop portion and being ejected 15

forwardly through the dispensing opening as the plate swings forward, and a spring yieldingly urging the plate forward, said abutment closing said dispensing opening when urged forward. 70

2. In a cigarette dispenser, a container having a lateral opening unobstructed from below and near the base thereof, a movable plate in the receptacle having an abutment normally registering with said opening and a portion curving upwardly from the abutment on which cigarettes are supported, a finger extending down from the plate and out through the base of the container for actuation of the plate, and means for limiting the movement of the finger, said abutment and the adjacent portions of the walls of the container forming a pocket to receive a single cigarette at the opening when the finger is pushed inwardly by the operator and push it out when the finger is released. 80 85 90
